The ornamental design for a martial arts uniform, as shown and described.

DESCRIPTION

FIG. 1 is a front perspective view of a martial arts uniform showing my new design, in an open configuration; FIG. 2 is a rear perspective view thereof, showing a portion of each sleeve removed for clarity of illustration; FIG. 3 is a front perspective view thereof, showing the martial arts uniform in a closed configuration; FIG. 4 is a front elevation view thereof; FIG. 5 is a back elevation view thereof; FIG. 6 is a left side elevation view thereof; FIG. 7 is a right side elevation view thereof; FIG. 8 is a top plan view thereof; and, FIG. 9 is a bottom plan view thereof.
FIG. 2 has been shown with a portion of each sleeve removed to clearly depict the interior pockets of the design. The broken lines in FIG. 2 represents an illustrative removal of a portion of a sleeve, in order to reveal the appearance of interior design features. This is understood to mean that the sleeve is continuous as shown in the corresponding views.
